UNITED STATES PATENT OFFICE.

GEORGE G. SCHROEDER, OF WASHINGTON, DISTRICT OF COLUMBIA.

TRACTION-ENGINE.

SPECIFICATION forming part of Letters Patent No. 447,978, dated March 10, 1891.

Application filed August 28, 1890. Serial No. 363,379. (No model.)

To all whom it may concern:

Be it known that I, GEORGE G. SCHROEDER, a citizen of the United States, residing at Washington, in the District of Columbia, have 5 invented certain new and useful Improvements in Traction-Engines; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention is in the nature of a traction-engine, and has for its object to improve such engines in such a manner as to make them more effective in operation when passing over rough and uneven ground.

With this object in view my invention consists in the improved construction, arrangement, and combination of parts hereinafter described, and afterward specifically pointed out in the claims hereto appended.

In the accompanying drawings, Figure 1 is 25 a top plan view of a traction-engine constructed in accordance with my invention, parts of the platform being broken away and the seat omitted. Fig. 2 is a view of the same in side elevation, the side bar of the frame being 30 broken away, its rear bar being shown in vertical section, and the pitman and sliding head being shown in dotted lines. Fig. 3 is a front elevation of the engine, the parts being in the position they assume when the central portion 35 of the track over which the engine is passing is elevated above the sides thereof. Fig. 4 is a view similar to Fig. 3, the parts being changed, however, to the position they assume when the central portion of the track 40 over which the engine is passing is depressed below the sides thereof. Fig. 5 is a view of the rear end of the engine, the traction-wheel and side bars of the frame being shown in transverse vertical section, the rear bar of the 45 frame being omitted, and the rest of the engine being shown in elevation. Fig. 6 is a view in side elevation of one of my compensating driving or sprocket wheels detached from the engine. Fig. 7 is a view of the same 50 in front or rear elevation. Fig. 8 is a detail view showing the compensating driving mechanism and traction-wheel supporting spring

and frame in side elevation and upon an enlarged scale. Fig. 9 is a similar view to Fig. 8, showing the parts in a modified form. 55

Like letters of reference mark the same parts wherever they occur in the various figures of the drawings.

Referring to the drawings by letter, A is the frame of the machine, consisting of side 60 bars *a a''* and rear bar *a''''*, the side bars being converged toward each other until they join at the extreme front end, where an upright bar *A''* is swiveled. Above the frame this bar is provided with a hand-wheel bar or other 65 suitable means, as at *A'''*, whereby it may be rotated on its axis. Below this frame this bar is formed at B as a fork, in which is journaled the guiding-wheel *B''*, the arms of said fork B having backward and upward extensions *B''''*, in the upper end of which is mounted a roller *b*, which bears against the under side of an arc-shaped track *b''*, secured 70 under the platform and frame-work.

Upon the frame-work is supported a boiler 75 C, having the parts usual thereto and of any desired well-known construction, the cylinders *c c''* being mounted at the sides and the piston-rods *c'''* projecting therefrom in a rearward direction. Sliding heads of ordinary construction connect these piston-rods with the pitmen *D D''*, which at their rear ends are connected to cranks *d d''* on a shaft 80 E, extending across the machine and mounted in suitable bearings depending from the side 85 bars of the front.

On the shaft E are secured rigidly sprocket-wheels *F F''*, over which pass drive-chains *G G''* to sprocket-wheels *H H''*, rigidly secured to a shaft I, journaled in bearings *i i''* in the inner bars *J J''* of a heavy metal frame-work K, which consists, besides said inner side bars, of outer side bars *j j''* and top bar *j'''* and horizontal projecting side bars *k k''*. The shaft I carries the traction-wheel L, which is 95 rigidly secured to it between the inner side bars *J J''*, and its bearings *i i''* are mounted to slide vertically in ways in the inner side bars and arranged below spiral or other springs *M M''* in said ways, secured at their 100 upper ends by nuts *m m''*.

The horizontal projecting bars *k k''*, heretofore mentioned, form axles projecting beyond the side bars of the frame and, secured

in the under sides thereof by clips n n'' , form the rear support for the frame. Upon these axles, outside the side bars of the frame, are mounted supporting-wheels N N'' , as shown.

5 The boiler and metal frame K are braced by means of rods O O'' , secured, as particularly shown in Figs. 1 and 2, to the boiler, metal frame, and rear bar of the main frame by bolts p p , p'' p'' , and p''' p''' , respectively.

An engine constructed as hereinbefore described would be operative and effective upon a level road, the operation being readily understood by the description given; but if the 15 road be rough and uneven the traction-wheel would at times be respectively horizontally even with, higher, and lower than the supporting-wheels. As a conspicuous result of this the distance between shafts E and I , which carry

20 the sprocket-wheels, will be variable and with an ordinary construction of sprocket-wheel and drive-chain would be impracticable, for the reason that if the chains were long enough to properly drive when the distance between 25 these shafts is greatest they would be too loose when such distance was shortened by reason of the changed position of shaft I , due to the movement up and down of shaft I , and if said chains were in length suitable to the 30 shortest distances they would break when the distance was increased. To provide against such contingencies is one of the objects of my invention, and my approved means are as follows: The sprocket-wheels are each com-

35 posed of a hub Q , spokes Q'' , radiating therefrom, a band q , having slots q'' , through which the outer rods of such spokes project, and a spring q''' around each spoke, having its inner bearing against the inside of the rim or 40 band. The band q is flexible and the springs

are sufficiently strong to give tension enough to the drive-chain for driving. When any change takes place in the level of the traction-wheel, and consequently the relative positions of the two sprocket-wheels are changed, 45 thus increasing their distance apart, the pressure of the drive-chains will cause the outer sides of the bands on the sprocket-wheels to move inward to a position some-

50 what similar to that shown in Fig. 8, and when the wheels reassume their natural or normal positions, as shown in Fig. 2, the springs being sufficient to cause proper tension of the drive-chains, as before stated, the springs M M'' will always cause the axle of the traction-wheel to assume its proper position and will always force it downward to bring the traction-wheel into effective contact with the roadway.

55 In Fig. 9 I have shown a modification wherein the movement of the traction-wheel up and down is guided in a circular track with the shaft E as a center, so that the distance between the shafts E and I is all the same, so that no lengthening or shortening of the drive-chains is necessary. In this modification ordinary sprocket-wheels are used, no

yielding bands or springs being necessary. The operation will be readily understood by an inspection of Fig. 9, and it will be understood that in all other respects an engine thus constructed will be the same as that shown in the other figures. The rims of the sprocket-wheels may be cut or lapped at the ends, if desired. 75

Having thus fully described my invention, what I claim, and desire to secure by Letters Patent of the United States, is—

1. In a traction-engine, the combination of a main frame, a shaft journaled thereon in stationary bearings, a frame-work secured to the main frame, having axial extensions and provided with yielding bearings for the traction-wheel, and connections therefrom, substantially as described, as and for the purpose set 80 forth.

2. In a traction-engine, in combination with the metal frame consisting of inner and outer side bars, top bar, and projecting axles, substantially as set forth. 90

3. In a traction-engine, a metal frame-work, substantially as described, consisting of the top bar, the inner side bars having slideways, the outer side bars, and the side projecting arms forming axles, as set forth. 95

4. In a traction-engine, in combination, supporting-wheels mounted on each side of the machine, a rigid metal frame-work, of which the axle of these wheels forms part, and a traction-wheel and axle yieldingly mounted 100 in said frame-work between said supporting-wheels; as set forth.

5. In a traction-engine, in combination, a stationary shaft, a yielding axle, a sprocket-wheel on each having a yielding band, and a 105 drive-chain connecting said sprocket-wheels, as set forth.

6. A sprocket-wheel consisting of a hub, a yielding band, spokes extending radially from the hub through said band, and springs for 110 supporting said band against extreme inward pressure, as set forth.

7. A sprocket-wheel consisting of a hub, a slotted band, spokes rigidly secured to the hub and projecting radially through the 115 slots in the band, and springs around the spokes bearing at their inner ends against the hub and at their outer ends against the band, as set forth.

8. In combination, the main frame, the 120 boiler secured therein, the traction-wheel-supporting frame, and the brace-rods connected to each of these parts, respectively, substantially as set forth.

9. In a traction-engine, the combination of 125 the main frame and its supporting-wheels, the frame-work having the side extensions to form axles for the supporting-wheels and provided with slideways for the bearings of the traction-wheel, the traction-wheel mounted 130 between the supporting-wheels, and springs to keep its bearings normally in their lower position, substantially as described.

10. In a traction-engine, the combination of

a main frame, a shaft journaled in said frame, carrying on its ends sprocket-wheels, with a frame-work secured to said main frame and provided with yielding bearings for the shaft of the traction-wheel, said shaft carrying on its ends sprocket-wheels connected to the sprocket-wheels of the stationary shaft, and means by which the outer peripheries of the

sprocket-wheels are maintained equidistant in all positions, substantially as described.

In testimony whereof I affix my signature in presence of two witnesses.
